Robert E. Holtgrieve and Gilbert R. Funk, Waukesha,
Wis., assignors to Waukesha Foundry Company,
Waukesha, Wis., a corporation of Wisconsin

Filed Nov. 23, 1960, Ser. No. 62,949

Term of patent 14 years

(Cl. D65—1)

FIG. 1 is a front perspective view of a metering pump showing my design.

FIG. 2 is a top plan view thereof, and

FIG. 3 is a view of the metering pump in side elevation, the opposite side being substantially the same in appearance as indicated in FIG. 2.

The dominant features of the design reside in the portions shown in full lines.

We claim:

The ornamental design for a metering pump, as shown and described.
